UNITED STATES PATENT OFFICE

157,788

STOCKING

Rebecca Rabinowitz, Philadelphia, Pa.

Application May 28, 1949, Serial No. 2,939

Term of patent 7 years

(Cl. D47—7)

To all whom it may concern:

Be it known that I, Rebecca Rabinowitz, a citizen of the United States, and a resident of Philadelphia, county of Philadelphia, State of Pennsylvania, have invented a new, original, and ornamental Design for a Stocking, of which the following is a specification, reference being had to the accompanying drawings, forming a part thereof, wherein:

Figure 1 is a fragmentary perspective view of the rear of the stocking, showing my new design; and

I claim:

The ornamental design for a stocking, as shown.
REBECCA RABINOWITZ.
